(57) **CLAIM**

We claim the ornamental design for a wearable movement monitor, as shown and described.

DESCRIPTION

FIG. 1 is a top, front perspective view of a wearable movement monitor showing the new design;

FIG. 2 is a top, rear perspective view thereof;

FIG. 3 is a perspective view thereof;

FIG. 4 is a front side view thereof;

FIG. 5 is a rear side view thereof;

FIG. 6 is a right side view thereof;

FIG. 7 is a left side view thereof;

FIG. 8 is a top view thereof; and,

FIG. 9 is a bottom view thereof.

The broken lines shown at the wrist band in FIGS. 1-5, 8 and 9 are included to indicate that a specific length of the wrist band of the monitor forms no part of the claimed design. The broken line showing of the docking station in FIG. 3 represents environmental subject matter. None of the broken lines form a part of the claimed design.
